UNITED STATES PATENT OFFICE

JOHN S. McWHIRTER, OF SOUTHPORT, CONNECTICUT, ASSIGNOR TO NATIONAL PNEUMATIC COMPANY, OF NEW YORK, N. Y., A CORPORATION OF WEST VIRGINIA

STEP MECHANISM

Application filed February 26, 1931. Serial No. 518,481.

This invention relates to improvements in step mechanism for vehicles.

One of the objects of this invention is the provision with a folding or sliding step for vehicles, of means controlled by the step for preventing its operation when a person is standing on the step or is caught on the step.

A further object of this invention is to provide a combination including a power operated step controlled from a point remote from the step, and means controlled by pressure on the step tread to prevent its actuation by the power device.

A still further object of this invention is the provision of a folding step used particularly in connection with the exit way of a vehicle which is normally remote from the point of control.

Another object of this invention is the provision of a step structure which is power actuated between two predetermined and adjustable limits of movement and arranged so that the tread of the step may be moved a short distance under pressure beyond which it is moved by power.

A still further object of this invention is the provision of power actuated step tread supporting arms, a tread movable a short distance with respect to said arms, and a switch or switches actuated by the additional movement of the tread.

These and many other objects, as will appear from the following disclosure are secured by means of this invention.

This invention resides substantially in the combination, construction, arrangement and relative location of parts, all as will be set forth in the following description.

Referring to the drawings:

Fig. 1 is a diagrammatic and schematic disclosure with some parts in cross section of the system of this invention;

Fig. 2 is a front elevational view of the step of this invention in folded position;

Fig. 3 is a cross sectional view taken on the line 3-3 of Fig. 2;

Fig. 4 is a cross sectional view with some parts broken away taken on the line 4-4 of Fig. 2.

In modern transportation systems it is now common practice to provide vehicles and especially buses with entrance and exit ways. The entrance ways are usually adjacent the vehicle operator's station, while the exit ways are remote from that point, as for example, in buses at the rear thereof. Likewise the so-called one-man street cars are provided with entrance ways at the front and exit ways at the rear. The operation of the barriers for the entrance and exit ways is either under the control of the operator or under the control of treadle plates adjacent the barriers and the operator. Thus there is a danger, especially in connection with the exit barrier that the vehicle operator attempt to close the exit barrier and its associated step at the time a person is leaving or entering the vehicle. The general object of this invention is the provision of a folding or otherwise movable step for the entrance and exit ways particularly the exit ways of vehicles, which controls the power operating mechanism when pressure is applied to the step tread.

This invention is similar in nature to the invention set forth in my copending application, Serial No. 518,480 filed Feb. 26, 1931.

Referring to the drawings the complete system is shown diagrammatically in Fig. 1. The platform of the vehicle adjacent the exit way for example, is shown at 1, from which depends two step supporting brackets 2 which are enclosed by a toe board 3. Supported from the brackets 2 for rotation, is the step shaft 4 to which is keyed for movement therewith, the step arms 5. The arms 5 are provided with rearwardly extending projections 6 to which are secured adjustable bolts 7 for engaging with the step hangers 2, to limit the unfolding or opening movement of the step.

Enclosing each of the arms 5 are the arms 8 in the form of casings as shown to the outer edge of which the tread 9 is secured. The arms 8 are freely and rotatably supported on shaft 4, so that they may rotate with respect thereto. Springs 10 are interposed between the tread 9 and the arms 5. Secured to shaft 4 is an arm 11 which is pivotally connected to the rod 12 by means of a coupling member 25. Pinned to the rod 12 in spaced relation are the collars 13 between which lie the springs 14 which lie against a sliding collar 15 which encircles the rod. This collar 15 is secured to a piston rod 16 of the differential fluid pressure operated engine 17. This engine is only disclosed diagrammatically since it is old and well known in many forms. At 18 is a source of fluid pressure which is permanently connected to the engine as shown by means of pipe 19 so that fluid pressure is always supplied to the engine between the two pistons of different diameters.

Also, the source of fluid pressure 18 is connected to the opposite side of the large piston of engine 17 by means of pipe 22, valve casting 20 and pipe 21. Valve casting 20 contains spring 41, valve 23, and valve 40, all so arranged that when solenoid 31 is de-energized the spring 41 keeps valve 23 closed and valve 40 open, thus connecting the right side of the large piston of engine 17 to atmosphere through pipe 21 and casing 20. In this condition fluid pressure acting between the pistons of engine 17 from source 18 through pipe 30 valve 40 keeps the pistons to the right and step arms 5 against their stop 38 (Figs. 2 and 4).

When the solenoid 31 is energized by any means such as the switch 33, current flows from the source 29 through wire 34 and switch 40 to wire 32, wire 27, the winding of solenoid 31 and wire 30 to the opposite side of the current source. This causes fluid pressure to flow from source 18 through pipe 22 to casting 20 and past valve 23, which has been opened by the energization of solenoid 31 to pipe 21 and the right side of the large piston of engine 17, the action of solenoid 21 having also closed valve 40 so that fluid pressure does not escape to atmosphere. The action of fluid at the same pressure on both sides of the large piston balances the effect of the large piston and piston rod 16 is driven to the left by the fluid pressure acting on the small piston. The movement of rod 16 to the left lowers the step arms 5 until they are stopped by bolt 7 and hanger 2.

The magnet valve construction is also well known in many forms. Mounted in the step tread 9 is a switch 26 arranged so that it will be closed when the tread 9 is moved downwardly with respect to the arms 5 against the reaction of spring 10. The fixed contacts of this switch are connected by wire 27 to one terminal of the magnet valve 20 and by wire 28 to one terminal of the current source 29.

The other terminal of the current source is connected by wire 30 to the other terminal of the magnet valve 20.

When the switch 26 has been closed by pressure on the tread 9, the solenoid 31 of magnet valve 20 is held energized, even though switch 33 may be open, thus keeping pressure on the right side of the large piston of engine 17 and keeping the step in its lowered position. Also, after switch 33 has opened and engine 17 has started to raise the step, if pressure is applied to tread 9, switch 26 will operate and by the energization of magnet valve 20 cause engine 17 to again lower the step.

The step structure itself is clearly shown in Figs. 2, 3 and 4. As stated, the step operating shaft 4 is rotatably mounted in brackets 2, which are supported from the car frame. An arm 11 suitably connected to shaft 4 is pivotally connected to the coupling member 25 which is attached to the rod 12. The arms 5 which are keyed to the shaft 4 for rotation therewith lie within enclosing arms 8 which are loosely mounted on shaft 4 for rotation about the shaft. Within the tread 9 are the switches 26 which may be of any suitable construction and arranged so that the movable member of the switch projects through the switch casing into a position to be engaged by the arms 5. The wires lead from these switches and out through a cable 40 which is protected by a flexible metal casing 41'.

As is clear from Fig. 2, arms 5 are rearwardly projecting arms to which are secured the adjustable bolts 7 which engage with the rearwardly extending flanges on the hangers 2. Figs. 2 and 4 show a collar 35 attached to the shaft 4 and provided with a projecting lug 36. Formed integral with the brackets 2 is a casing 37 which is likewise provided with a projecting lug, in this case number 38. When the step has been closed the lug 36 on collar 35 engages lug 38 on the casing 37 to prevent the step arms and their attached barriers from moving any further. Collar 35 is adjustably attached to the shaft so that the movement of the step to closed position may be adjustably controlled. Likewise the movement of the step to open position may be adjustably controlled by means of the bolt 7 which engages the rearwardly extending flange of the hangers 2. By means of these adjustable sides it is possible to effect movement of the step between two predetermined limits. When the step is fully open and pressure is applied thereto by persons standing on the step the tread rotates downwardly on the shaft 4 with respect to arms 5, compressing spring 10 and closing switch 26. The same is true if the step tread should catch on the clothing of a person when it is closing.

In the normal operation of the device switch 33 is closed by any suitable means, such as a passenger stepping on a movable plate in

the vehicle floor so constructed that pressure thereon causes the switch 33 to close, so that pipes 21 and 22 are interconnected. Fluid pressure is of course continuously supplied to the engine through pipe 19. When pipes 21 and 22 are interconnected by valve 20 fluid pressure is also supplied to the right hand end of the large cylinder. The pressure being the same on both faces of the large piston no external effect results and the pressure on the smaller piston causes both pistons which are united to move to the left carrying with it arms 16 and collar 15. Springs 14 are of such strength that the pressure is transmitted from collar 15 to rod 12 through the left hand spring 14 causing the step to move down to full open position. With this construction the pistons can be intentionally set to overtravel, for when they overtravel the 20 step moves down to the full open position and stops, the overtravel of the pistons being taken up by the compression of spring 14. It is highly desirable to initially adjust the pistons with an overtravel, for this overtravel is thus available to take up wear in the step operating mechanism as such develops, and this insures full travel of the step. When a person steps on the tread 9 so that switch 26 is closed current also flows from source 30 29 through switch 26 to hold magnet valve 20 energized. At this time if switch 33 is opened, magnet valve 20 remains energized by means of switch 26. Therefore the engine 17 will not operate to close the step or even 35 tend to close the step. Thus the operator cannot by accidentally moving his valve 23 to position B cause the step to close while there is any pressure on the tread sufficient to maintain switch 26 closed. As soon, however, as the tread is free, spring 10 moves it upwardly permitting switch 26 to open. As the result magnet valve 20 is de-energized and the fluid pressure on the right face of the large piston is again exhausted to atmosphere. 40 The fluid pressure acting between the pistons of engine 17 then drives piston 16 to the right and causes the step to close. It is apparent that overtravel of the pistons has been provided for in the closing of the step as well as in the opening already described.

Another advantage of the spring connection is that if the step should strike the body of a person when moving downwardly, or a person's foot or other object be caught between the step and the car body when it is moving upwardly, spring 14 can give so that no injury will result and the object may be withdrawn by pulling on the step tread.

It is apparent that more than one switch 60 may be mounted in the step tread 9. Fig. 2 shows two switches 26 mounted in the step tread. Where more than one switch 26 is used, one of the switches may be used as hereinbefore described and another switch 26 may 65 be used for some other purpose, for example

as set forth in my copending application, Serial No. 518,480 filed Feb. 26, 1931.

From the foregoing disclosure it will be apparent that this invention involves certain principles of construction and operation 70 which may be embodied in other physical forms without departure therefrom. I do not, therefore, wish to be strictly limited to the disclosure as given in an illustrative sense, but rather to the scope of the appended claims.

What I seek to secure by United States Letters Patent is:

1. A step mechanism of the type described comprising a rotatable step shaft, arms secured to said shaft for rotation therewith, and a step tread mounted on said shaft for movement therewith and arranged to be movable with respect to said arms. 80

2. A step structure of the type described comprising supporting hangers, a shaft rotatably supported in said hangers, arms secured to said shaft for rotation therewith, a step tread, and means for securing the step tread to said shaft to effect combined movement of the arms and tread and to permit movement of the tread with respect to the arms. 85

3. A step structure of the type described comprising supporting hangers, a shaft rotatably mounted in said hangers, arms secured to said shaft for rotation therewith, hollow casings enclosing said arms and mounted on said shaft for movement with respect thereto, and a tread mounted on said hollow casings whereby pressure on the tread permits movement of the tread and hollow casings with respect to the arms secured to the shaft. 95

4. A step structure of the type described comprising supporting hangers, a shaft rotatably mounted in said hangers, arms secured to said shaft for rotation therewith, hollow casings enclosing said arms and mounted on said shaft for movement with respect thereto, a tread mounted on said hollow arms whereby pressure on the tread permits movement of the tread and hollow casings with respect to the arms secured to the shaft, and resilient means between the arms 105 attached to the shaft and the tread for resisting movement of the tread with respect to the arms attached to the shaft.

5. A step mechanism of the type described comprising a rotatably supported shaft, rigid arms secured to said shaft, hollow arms freely mounted on said shaft and enclosing said rigid arms, a tread secured to said hollow arms, springs interposed between the tread and said rigid arms, and a switch mechanism 115 mounted on said tread and arranged so as to be closed when the tread and hollow arms are moved with respect to the rigid arms. 120

6. A step mechanism of the type described comprising a rotatably supported shaft, rigid 125

5 arms secured to said shaft, hollow arms freely mounted on said shaft and enclosing said rigid arms, a tread secured to said hollow arms, spring interposed between the tread and said rigid arms, and adjustable means for limiting the movement of the rigid arms and shaft at each end of their travel.

10 7. In a step structure the combination with hangers and a shaft rotatably supported therein, of arms fixed to said shaft, stops for limiting the movement of the shaft in either direction, arms loosely mounted on said shaft, and a tread secured to said arms and loosely mounted on said shaft, said tread and 15 arms loosely mounted on said shaft cooperating with the arms fixed to said shaft for limiting the movement of the tread in either direction.

20 8. A step structure of the type described comprising the combination with hangers, a shaft rotatably supported in said hangers and rigid arms fixed to said shaft, of stops for limiting the movement of the shaft, arms loosely attached to the shaft, a tread mounted on said arms and springs interposed between said tread and rigid arms to resist movement of the tread with respect to the rigid arms.

25 9. A step structure of the type described comprising hangers, a shaft rotatably supported in the hangers, rigid arms attached to said shaft, hollow arms loosely attached to said shaft, a tread secured to said hollow arms, the hollow arms and tread permitting 30 but limiting the movement of the tread with respect to the rigid arms, springs for resisting the movement of the tread with respect to the rigid arms, and switch means mounted on the tread so as to be operated when the tread moves with respect to the rigid arms.

35 10. A step structure of the type described comprising a rotatable shaft, rigid arms attached to said shaft, stop means for limiting the movement of the shaft and a tread mounted on said shaft and movable with respect to the rigid arms.

40 11. A step structure of the type described comprising a rotatable shaft, rigid arms attached to said shaft, stop means for limiting the movement of the shaft, a tread mounted on said shaft and movable with respect to the rigid arms, and means for limiting the movement of the tread with respect to the rigid arms.

45 12. A step mechanism as described comprising a rotatable shaft, arms secured to said shaft, a tread attached to said arms, a motive device, and spring connecting means for connecting the motor device to said shaft whereby the springs will take up overtravel of the motive device.

50 13. A step mechanism as described comprising hangers, a shaft rotatably supported in said hangers, rigid arms secured to said shaft, means for limiting the movement of

55 said shaft in either direction, a tread loosely mounted on said shaft and movable with respect to said rigid arms, a motive device and means for connecting the motive device to said shaft including springs whereby the parts comprising the step may be moved manually with respect to the motive device.

60 14. In an apparatus of the type described the combination comprising a movable step, motive means for moving said step, a source of energy, means for controlling the supply of energy from the source to the motive device, and means controlled by the step when pressure is applied thereto for preventing the supply of energy from the source to the motive device.

65 15. In an apparatus of the type described the combination comprising a folding step including a movable tread, motive means for operating the step, a source of energy connected to said motive means, means for controlling the supply of energy from the source to the motive means, and means controlled by the movement of the tread for rendering the means for controlling the supply of energy ineffective.

70 16. In an apparatus of the type described the combination comprising a movable step having a movable tread, a fluid pressure motor connected to said step for moving it, a source of fluid pressure connected to said fluid pressure motor, a valve for controlling the supply of fluid pressure to the motor, and means controlled by the movement of the tread under a pressure for preventing the motive device from being operated by the valve to move the step to closed position.

75 17. In an apparatus of the type described the combination comprising rotatably supported step arms, a tread movable with respect to said step arms, a switch mounted on said tread to be closed when it moves with respect to said arms, means for moving said step arms including a motive device, a source of energy, means for controlling the supply of energy from the source to the motive device, and auxiliary means connected to said switch for rendering said controlling means ineffective when the tread is moved with respect to the step arms.

80 18. A step mechanism as described comprising a rotatable shaft, arms secured to said shaft, a tread supported by said shaft, stop means for limiting the movement of the arms in either direction, a motive device and spring connecting means between the motive device and said shaft whereby when said stops become effective over travel of the motive device will be absorbed by said spring connection.

85 19. In a mechanism as described the combination of a folding step comprising movable arms and a tread movable with said arms and with respect thereto under pressure, a motive device connected to said step for opening and closing it, a source of energy for the motive

device, means for normally controlling the supply of energy from the source to the motive device to open and close the step at will, and means operated by the tread when pressure is applied thereto for rendering the control means ineffective.

20. The combination with a folding step and power means connected thereto for operating it, of control means for the power means associated with said step to be operated when pressure is applied to the step to prevent movement of the step by the power means.

In testimony whereof I have hereunto set my hand on this 31st day of January A. D., 1931.

JOHN S. McWHIRTER.
